Primary Examiner — George D Kirschbaum*Assistant Examiner* — Jennifer Watkins*(74) Attorney, Agent, or Firm* — Alston & Bird LLP(57) **CLAIM**

I claim the ornamental design for an orthotic support, as shown and described.

DESCRIPTION

FIG. 1 is a perspective view of an orthotic support showing my new design;

FIG. 2 is another perspective view thereof;

FIG. 3 is a rear perspective view thereof;

FIG. 4 is a right perspective view thereof;

FIG. 5 is a top perspective view thereof;

FIG. 6 is yet another perspective view thereof, shown in a situation of use;

FIG. 7 is a front elevation view thereof;

FIG. 8 is a rear elevation view thereof;

FIG. 9 is a right side elevation view thereof, the left side elevation view being a mirror image thereof; and,

FIG. 10 is a top plan view thereof.

The broken lines in FIGS. 3 and 8 represent portions of the orthotic support that form no part of the claimed design. The broken lines showing a human form in FIG. 6 represent environment and form no part of the claimed design.
